BUTTON SEWING MACHINE

Franklin A. Reece, Brookline, Mass.

Original application January 24, 1936, Serial No. 60,616. Divided and this application June 6, 1936, Serial No. 83,943

22 Claims. (CL. 112—110)

This invention relates to machines for sewing on buttons, especially substantially flat buttons having perforations or holes through which the attaching thread is passed. Such buttons are of a wide variety of shapes and sizes, the number of the thread receiving holes differing in different buttons, and the number of stitches required for their satisfactory attachment varying with the number of holes, the size of the buttons, and the purpose and location of their attachment.

The present invention has for a general object the provision of an improved button sewing machine which can, by simple adjustments readily effected by the ordinary operator, be set to attach a button by means of a variable number of groups of stitches of a predetermined number of stitches each, the thread being secured by a tying stitch at the completion of each group of attaching stitches. The machine is entirely automatic in its operation and, having been set in operation with the work properly positioned therein, will perform and complete the sequence of operations for which it has previously been set or adjusted and thereafter come to rest.

The more particular objects of the invention, together with means whereby the latter may be carried into effect, will best be understood from the following description of an illustrative embodiment thereof shown in the accompanying drawings. The particular mechanism described and shown has, however, been chosen for purposes of exemplification merely, as it will be obvious to those skilled in the art that the invention as defined by the claims hereunto appended, may be otherwise embodied without departure from the spirit and scope thereof.

In said drawings:

Fig. 1 is a side elevation, partly broken away, of the complete machine.

40 Figs. 2 and 3 are detail views illustrating the attachment of two different types of buttons.

Fig. 4 is a horizontal section taken substantially on the line 4—4, Fig. 1.

Fig. 5 is a horizontal section taken substantially on the line 5—5, Fig. 1.

Fig. 6 is a vertical section taken substantially on the line 6—6, Fig. 1.

Fig. 7 is a plan view, and

Fig. 8 a side elevation of the main cam.

50 Fig. 9 is a section taken on the line 9—9, Fig. 8.

Fig. 10 is a detail section taken substantially on the line 10—10, Fig. 5.

Fig. 11 is a detail section taken substantially on the line 11—11, Fig. 10.

55 Fig. 12 is a fragmentary longitudinal vertical section taken substantially on the line 12—12, Fig. 16, of the rear portion of the machine, showing certain of the driving connections.

60 Figs. 13, 14 and 15 are fragmentary detail views

of certain of the parts in Fig. 12 showing them in different positions.

Fig. 16 is a horizontal section taken substantially on the line 16—16, Fig. 12.

Fig. 17 is a detail section taken substantially on the line 17—17, Fig. 12.

Fig. 18 is a fragmentary detail view of certain of the parts in Fig. 12.

Figs. 19 and 20 are detail sections taken substantially on the lines 19—19 and 20—20, respectively, Fig. 16, showing the parts in different positions.

Although not limited to use in connection with button sewing mechanism of any particular type, the invention is herein illustrated in connection with a button sewing machine of the character disclosed and claimed in a prior application, Serial No. 60,616, filed January 24, 1936, of which this case is a division, and in order to make clear the purpose and operation of the mechanism to which the present invention relates, the general construction and operation of the machine of said prior application will be briefly outlined.

Referring to Figs. 1, 4, 5 and 6, the frame or casing of the machine comprises a base or bed 10 and an overhanging head 11 supported therefrom by an upright housing portion 12 enclosing the principal parts of the operating and controlling devices. For convenience of assembly and repair, said frame or casing comprises two separable main sections A' and A2 connected and relatively positioned by dowels a (Figs. 4 and 12) and several attached minor parts all of which collectively afford the necessary enclosures, supports, bearings, etc., for the various moving parts.

The bed 10 carries a work plate 13 upon which the fabric W to which the buttons are to be attached is supported and against which it is clamped by a presser foot 14 carrying a button clamp 15 for holding the individual buttons and positioning them for the operation of the sewing instrumentalities.

The main driving and controlling instrumentalities include a main power shaft 16 journaled in suitable bearings in the head 11 and to which power may be applied through a belt pulley 17 under the control of automatic stop mechanism hereinafter described; a vertical cam shaft 18 journaled in suitable bearings in the housing 12, driven through a worm 25 and worm gear 26 from the main shaft 16, and provided with suitable cams for controlling the movements of the several instrumentalities; and a horizontal looper shaft 19 journaled in suitable bearings in the base 10 and operated and controlled from the cam shaft 18.

The stitch-forming instrumentalities include an eye-pointed needle 80 carried by a needle bar 81 mounted for vertical or longitudinal reciprocation in the head 11, and a pair of loopers 82 and 83

on a looper carrier 84 secured to the looper shaft 79 adjacent its forward end, (see particularly Fig. 5). Except as hereinafter mentioned, these instrumentalities may be substantially as shown and described in the United States patent to Dahl, No. 862,238, August 6, 1907.

In attaching a two-hole button B, as shown in Fig. 2, the carrier 98 for the lower needle bar bearing is oscillated laterally between successive descents of the needle 80 to cause said needle to pass alternately through the holes h and h^x in the button, the looper carrier being at this time oscillated laterally by the shaft 79 to cause the loopers to cooperate with the needle in the formation of the stitches s passing through said holes and serving to attach the button to the fabric W. In attaching a four-hole button, such as shown at B' in Fig. 3, the same operations are performed to form a series of attaching stitches s' passing through the holes h1 and h2, after which the carrier 98 is shifted longitudinally or in a direction fore and aft of the machine, to bring the needle into the plane of the holes h3 and h4 of the other pair, the looper shaft 79 with the looper carrier 84 and loopers 82 and 83 being similarly shifted to maintain the cooperative relationship of said loopers with the needle. Thereafter the sewing operations are repeated to form a second set of attaching stitches s2 passing through the holes h3 and h4.

The carrier 98 is oscillated laterally about the axis of its pivot 107 to cause the needle to pass alternately through the holes h, h^x (Fig. 2), h', h2 (Fig. 3) or h3, h4, by mechanism more fully described in said prior application. Generally speaking, said mechanism comprises a link 113 suitably connected at one end with the carrier and provided at the opposite end with a stud 120 received in an arcuate groove 121 in one arm 40 of a lever 122 (see also Fig. 6) secured to an upright shaft 123 journaled in the casing. At its opposite end the lever 122 carries a pin 125 which engages a cam groove 127 in the upper face of a main cam 129 fast on the vertical cam shaft 78. With this construction it will be seen that rotation of the cam 129 will cause the lever 122 to swing about the axis of the shaft 123, and that this movement will be transmitted from said lever to the carrier 98 through the link 113.

The amplitude of the lateral vibration thus imparted to the carrier 98 will depend upon the point of engagement of the stud 120 with the groove 121, and in order to permit this to be readily adjusted in accordance with the lateral spacing of the holes in the button, the link 113 is provided with a stud 130 engaged by a fork 131 (see also Fig. 4) which may be suitably adjusted.

The mechanism for moving the carrier 98 longitudinally comprises a link 146 (Fig. 4) having at its forward end a stud received in a transverse groove or way in the upper face of the carrier 98 adjacent the rear end of the latter. At its rear end the link 146 carries a stud 151 which engages a groove 152 in an arm 153 secured to a second vertical rock shaft 154. Adjacent its lower end the rock shaft 154, has secured thereto an arm 155 (Fig. 5) having a bifurcated end between the branches of which is pivoted the end of a link 156 which has secured thereto a pair of contact or cam-follower blocks 161 embracing between them and cooperating with an edge cam 162 rotatably mounted on the stud 158 and the hub of which is provided with a spur gear 163 meshing with a pinion 164 on the lower end of the main cam shaft 78. The gear 163 and pinion

164 are of such sizes as to constitute two to one gearing between the cam 162 and the cam shaft 78, so that the cam 162 is rotated at one-half the speed of the main cam 129. Accordingly, after one complete rotation of the cam 129 to cause the cam groove 127 thereof to produce a predetermined number of lateral reciprocations of the needle bar to form, for example, the group of stitches s' (Fig. 3), the cam 162 will cause the carrier 98 and needle bar to be shifted longitudinally of the machine in one direction, after which a second rotation of the cam 129 will cause the necessary number of lateral reciprocations to form the group of stitches s2, whereupon the cam 162 will return the carrier and needle bar to their original longitudinal positions.

The amplitude of the longitudinal or fore and aft movement of the carrier 98 and needle bar 81 is determined by the position of the stud 151 in the groove 152 of the arm 153, and, in order that this may be conveniently adjusted in accordance with the fore and aft spacing of the holes h1, h2 and h3, h4, there is provided a fork 165 (Figs. 1, 4 and 6) which is operated from the exterior of the casing by a hand lever 169.

Fig. 4 shows the adjustment of the parts for a four-hole button having the maximum hole spacing for which the machine is adapted.

The oscillations of the looper shaft 79 are effected by mechanism more fully shown and described in application Serial No. 60,616, above referred to. Said mechanism includes a sleeve 179 (Figs. 1 and 5) in which the rear end of said shaft is slidably mounted and a collar 180 secured to the shaft, said sleeve and collar constituting a slip coupling or clutch connecting the sleeve and shaft for oscillation in unison while permitting longitudinal movement of the shaft in the sleeve. At its rear end the sleeve 179 is formed with a head 181 having a transverse bore in which a stud 183 is rotatably and slidably mounted. The stud 183 is provided with a head 184 having a transverse bore in which is slidably and rotatably received a stud 185 projecting from the end of an arm 186 secured to one end of a transverse rock shaft 187. By these connections the shaft 187 and sleeve 179, although disposed perpendicular to one another, are connected for oscillation in unison. At its opposite end the rock shaft 187 has secured thereto an arm 188 to which is pivoted the lower end of a link 190. At its upper end the link 190 is provided with a stud 191 the inwardly projecting end of which is received in an arcuate groove 192 in one end of a lever 193 fulcrumed at its opposite end on a stud 194 projecting inwardly from the side wall of the housing 72. Intermediate its ends the lever 193 carries a pin 195 engaging a cam groove 197 formed in the side or periphery of the main cam 129. The groove 197 corresponds to the groove 127, that is to say, the number and timing of the oscillations of the looper shaft 79 produced by the former correspond to the number and timing of the lateral oscillations of the needle produced by the latter. The amplitude of oscillation of the looper shaft 79 depends upon the position of the stud 191 in the groove 192 of the lever 193, and in order that this position may be suitably adjusted concurrently with the adjustment of the position of the stud 120 in the groove 121 of the lever 122, the slide 132 by which the latter stud is adjusted is provided with a depending flange 202 (Fig. 1) having a slot 203 to receive the outwardly projecting end of the pin 191.

When the needle bar carrier 98 is shifted longitudinally or in a direction fore and aft of the machine, the looper shaft 79 is likewise shifted longitudinally to maintain the proper cooperative relationship of the loopers to the needle. This is effected by a vertical rock shaft 150, whose arm 149 is connected with the link 146. This shaft has secured to its lower end a second arm 204 connected by a link 205 with a fork 206 through openings in the arms of which the looper shaft 79 extends and whose arms embrace a collar 207 secured to said looper shaft, whereby, when the carrier 98 is shifted longitudinally by the lever 153 acting through the link 146, the shaft 79 will be correspondingly shifted longitudinally.

The main cam 129 makes one complete rotation for each group of stitches *s*, *s'* or *s2*, and the number of stitches of each group is determined by the shape of the cam grooves 127 and 197. Referring to Fig. 7, the cam groove 127 is formed with five radially offset portions, adapted to produce five complete lateral reciprocations of the needle in synchronism with the vertical reciprocations thereof, and with a concentric portion 231 during which the needle is caused to make two descents through the same hole in the button in order to form a knot or tying stitch, and the groove 197 is correspondingly formed to produce the requisite oscillatory movements of the loopers 82 and 83 to cause them to cooperate alternately with the needle in the formation of the attaching stitches and with a portion 273 so shaped as to cause one of said loopers to cooperate twice in succession with said needle when the latter descends twice through the same hole in the formation of the tying stitch. Consequently, each group of stitches will comprise ten attaching stitches and a tying stitch, the whole group requiring twelve vertical reciprocations of the needle.

The belt pulley 77 (Fig. 1) is loose on the shaft 76 and is adapted to be clutched thereto by a combined clutch and stop mechanism which as herein shown is similar to those shown and described in the United States patent to Mello, No. 1,227,643, May 29, 1917, and United States patent to Reece, No. 1,730,014, October 1, 1929. Referring to Fig. 19, said mechanism includes a ring 276 carried by the pulley 77 and having a pin 277 which projects through a slot 278 in said pulley and is engaged by a spring 279 located in a recess in said pulley, whereby said ring is permitted a limited yielding angular movement with respect to the pulley, in order to cushion the shock of starting. The ring 276 has a shoulder 280 adapted to be engaged by a clutch dog 281 pivoted at 286 to a hub 282 keyed to the shaft 76 and normally urged into engagement with said shoulder by a spring 283 connecting said dog with an arm 284 fixed to said hub. The dog 281 is formed with a stop arm 285 adapted, when the connected parts are rotated in the direction of the arrows on Figs. 18, 19 and 20 to engage a head 287 yieldingly mounted by means of a spring 288 in the end of a stop arm 289 when the latter is in the position shown in full lines in Fig. 13, thereby disengaging the dog 281 from the shoulder 280 as shown in Fig. 18, and stopping the rotation of the shaft 76, the shock of stopping being cushioned by the spring 288. Recoil of the shaft under the influence of the spring 288 is prevented by a pawl 290 normally urged into a position to be engaged by a shoulder 291 on the hub 282 by means of a spring 292. The arm 289 is formed with a cam surface 293 which coop-

erates with a plunger 294 slidably mounted in the frame and engaging the pawl 290. The arrangement of the parts is such that, when the stop arm 289 is in the position shown in dotted lines in Fig. 13, the head 287 is out of the path of movement of the arm 285 of the dog 281, permitting the latter, under the influence of the spring 283, to engage the shoulder 280, as shown in Fig. 20, thereby connecting the pulley 77 and hub 282 for rotation in unison in the direction of the arrows. The cam surface 293 at the same time acts through the plunger 294 to hold the pawl 290 in the inoperative position shown in Fig. 20. When the stop arm 289 is in the position shown in full lines in Fig. 13, the head 287 will be engaged by the stop arm 285 to disconnect the parts and stop the machine, as above described. The cam surface 293 at this time permits the plunger 294 to be forced back by the spring 292, thereby permitting said spring to move the pawl 290 into operative position for engagement by the shoulder 291, as shown in Fig. 18.

The stop arm 289 is secured, as by a set screw 307, (Figs. 17 and 18), to a rock shaft 305 journaled in the frame and having secured thereto at the exterior of the casing an arm 306 (Figs. 1, 16 and 17) connected by a chain 295 (Fig. 1) with a suitable treadle (not shown), said arm being preferably provided with a spring pressed positioning plunger 296 adapted to engage either one of the two recesses or depressions 297 (Figs. 1 and 17) in the outer wall of the casing, thereby releasably retaining the stop arm 289 in either of the two positions shown in Fig. 13. To start the machine, the treadle is depressed, thereby rocking the shaft 305 in the direction to move the stop arm 289 into the position shown in dotted lines in Fig. 13. The machine having been started will continue to operate until automatically stopped. For this purpose the following mechanism is provided:

Secured, as by a set screw 308 (Fig. 18), to the inner end of the rock shaft 305 is an arm 298 having a bifurcated end between the bifurcations of which is pivoted a bunter 299 having a bevelled free end 300 (Fig. 17) adapted, when said bunter is in the elevated position shown in Figs. 13 and 15, to be engaged by a stud 301 projecting from the underside of the main cam 129 when the latter reaches an angular position corresponding to the completion of a group of stitches of the number determined by the shape of the cam grooves 127 and 197. Such engagement of the end 300 of the bunter 299 by the stud 301 causes said bunter to be forced toward the right in Fig. 13, thereby rocking the shaft 305 in a clockwise direction and moving the stop arm 289 into the position shown in full lines in Fig. 13 to disengage the clutch and stop the machine. The stud 301 is preferably notched, as shown at 302 in Fig. 9, so that the slight overthrow of the parts incidental to stopping the machine will bring said notch opposite the end of the bunter 299 in order to permit the machine to be again started by operation of the treadle.

A shaft 265 (Figs. 6, 10 and 11) is journaled in the frame and provided at the exterior of the casing with an operating handle 266 whereby it may be conveniently turned. Said shaft is formed with a flattened end portion 303 (Fig. 18) adapted, when said shaft is turned into the position shown in Fig. 15, to hold the bunter 299 in its operative position in the path of movement of the stud 301 to stop the machine after one complete rotation of the cam 129 and the

consequent completion of one group of attaching and tying stitches, as in sewing a two-hole button B, Fig. 2. When turned into the position shown in Figs. 14, 16 and 18, however, the flattened portion 303 permits the bunter 299 to be drawn by a spring 304 into the inoperative position shown in Fig. 14 out of the path of movement of the stud 301, thereby permitting the continued operation of the machine after one complete rotation of the cam 129, as in sewing two groups of stitches attaching a four-hole button B' (Fig. 3), until raised into its operative position by the following mechanism:

Pivoted as at 309 (Figs. 13, 14 and 17) to the frame member 159 is a bell crank lever having one arm 310 in engagement with a vertically sliding plunger 311 guided in said frame member and adapted, when raised, to lift the bunter 299 from the inoperative position shown in Fig. 14 into the operative position shown in Figs. 13 and 15. The other arm 312 of said bell crank lever engages a cam or eccentric 313 formed on the hub of the gear 163 and cam 162. The cam and gear assembly 162, 163, 313 makes one complete rotation to two complete rotations of the cam shaft 78 and main cam 129, and the eccentric 313 is so arranged that the completion of one rotation of the cam 129 the bell crank 310, 312 and plunger 311 will be in the positions shown in Fig. 14, but at the completion of a second rotation of the cam 129 said parts will be in the position shown in Fig. 13, thereby lifting the bunter 299 into operative position and causing the stopping of the machine upon the completion of said second rotation.

It will thus be seen that with the shaft 265 in the position shown in Fig. 15 the machine will be stopped after the completion of one group of attaching and tying stitches, and when said shaft is in the position shown in Figs. 13 and 14, the machine will be stopped after the completion of two groups of attaching and tying stitches. By a suitable angular setting of the shaft 265 by means of the handle 266, the machine can be set to complete automatically either one group of stitches resulting from twelve vertical reciprocations of the needle, or two such groups of stitches. The shaft 265 is mounted for a limited longitudinal movement in opposition to a spring 314 (Figs. 6 and 10) interposed between the casing wall and a collar 315 on said shaft, said spring normally holding the shaft in the longitudinal position shown. Secured to the shaft 265 immediately adjacent the outer face of the casing wall is a disk 316 (Figs. 10 and 11), said disk being preferably formed integral with the handle 266 and the whole unit being secured to the shaft by a key 317. The disk 316 is provided adjacent its edge with two index characters 318 and also carries a stud 319 adapted to engage either of two apertures 320 in the casing wall, whereby the angular position of the shaft may be fixed with either of the index characters 318 opposite a fixed index or reference pin 321. By drawing the shaft 265 outwardly a limited distance against the tension of the spring 314, the stud 319 may be disengaged from the aperture 320 with which it is engaged, the shaft turned to bring the other index character 318 opposite the reference pin 321, and the shaft released to permit the spring 314 to re-engage the pin 319 with the other aperture 320; thereby locking the shaft in readjusted position. As shown the index characters 318 comprise the numerals "1" and "2" disposed at 90° to one

another. The arrangement is such that when the numeral "1" is opposite the index pin 321, the shaft 265 is in the position shown in Fig. 15, so as to stop the machine after one rotation of the cam 129 and consequently upon the completion of one group of attaching and tying stitches, and when the numeral "2" is opposite the index pin, the shaft 265 is in the position shown in Figs. 13 and 14, so that the machine is not stopped until after two rotations of the cam 129 10 and the completion of two groups of stitches.

In order to set the machine to sew a two-hole button B (Fig. 2), the pin 151 is adjusted into a position coaxial with the shaft 154. The slide 132 (Fig. 6) is adjusted, in accordance with the lateral spacing of the holes h , hx (Fig. 2), to position the studs 120 and 191 at the proper points in the grooves in their respective lever arms 122 and 193 to give the required amplitude of lateral vibration to the needle and loopers. The shaft 265 (Figs. 6, 10 and 11) is angularly set to stop the machine upon the completion of one group of stitches, that is to say, the index numeral "1" is set opposite the reference pin 321. The starting treadle (not shown) is then depressed and acts through the chain 295 (Fig. 1) and arm 306 to rock the shaft 305 (Fig. 13) in a counter-clockwise direction, thereby disengaging the head 287 of the stop arm 289 from the arm 285 (Figs. 18, 19 and 20) of the clutch dog 281 and starting the machine. During the operation of the machine the rock shaft 305 is retained in the position into which it has been moved by the starting treadle by engagement of the plunger 296 (Fig. 17) with the appropriate recess 297. The machine thereupon operates to cause the needle to descend alternately through the holes h and hx and the looper mechanism to cooperate therewith to form a group of attaching stitches, and thereafter to cause said needle to descend twice through the same hole to form a tying stitch. Upon the completion of this stitch group, i. e., upon the completion of one rotation of the cam 129, the stud 301 (Figs. 15 and 17) engages the end of the bunter 299, forcing the same toward the right and thereby rocking the shaft 305 in a clockwise direction and moving the stop arm 289 into the position shown in full lines in Fig. 13. The arm 285 of the clutch dog 281 thereupon engages the head 287 of said stop arm, thus disengaging the clutch and positively stopping the shaft 76, the impact being cushioned by the spring 288. Movement of the stop arm 289 into stopping position causes the cam surface 293 (Fig. 16) on said arm to release the plunger 294 (Figs. 16 and 18), so that the spring 292 moves the pawl 290 into position to be engaged by the shoulder 291 to check the recoil of the spring 288, as shown in Fig. 18.

In order to set the machine to sew a four-hole button B' (Fig. 3), the stud 151 is set at the proper point in the groove 152 in the lever arm 153 to produce the requisite fore and aft shifting movement of the needle and looper mechanism in accordance with the fore-and-aft spacing of the pairs of holes h^1 , h^2 and h^3 , h^4 . The adjustment for lateral hole spacing is made by the slide 132 (Fig. 6) in the same manner as above described in the case of a two-hole button. The shaft 265 (Figs. 10 and 11) is angularly set with the index numeral "2" opposite the reference pin 321, thereby positioning the flattened end portion 303 thereof as shown in Figs. 13 and 14. The machine then operates as above 75

described to sew a group of attaching and tying stitches through the holes h^1 and h^2 . Upon the completion of this stitch group, the cam 129 will have made one complete rotation, but at this time the eccentric 313 permits the bell crank 310, 312 and plunger 311 to assume the positions shown in Fig. 14, so that the bunter 299 is not engaged by the stud 301, and the operation of the machine continues. Also at the completion 10 of the first stitch group and the first rotation of the cam 129, the cam 162 acts, through the slide 156, rock shaft 154, lever arm 153, link 146, arm 149, and rock shaft 150, to shift the needle and looper mechanism rearwardly into position to 15 cooperate with the holes h^3 and h^4 , whereupon a second group of stitches is sewn through the latter holes. Meantime, the eccentric 313 has been turned into a position to rock the bell crank 310, 312 and lift the plunger 311 and bunter 299 20 into the position shown in Figs. 13 and 15. Consequently, upon the completion of the second group of stitches and the second rotation of the cam 129, the stud 301 will engage the bunter 299 and stop the machine as above described.

25 If it be desired to sew a two-hole button with a number of stitches greater than that of the single stitch group for which the machine is designed, the parts may be so adjusted as to sew two groups of stitches through the same pair of holes, each group being completed by the usual tying stitch. For this purpose the pin 151 is positioned concentric with the shaft 154, and the shaft 265 (Figs. 10 and 11) turned to bring the index numeral "2" opposite the reference pin 321, the other adjustments being as above described. The operation of the machine, after depression of the starting treadle, will then be as above described in connection with the sewing of a four-hole button except that there will be no 40 fore and aft shifting of the needle and looper mechanism after the completion of the first stitch group, so that both groups of stitches will be sewn through the same pair of holes.

I claim:

- 45 1. In a machine for sewing on buttons, stitch forming mechanism, means for operating the same in cycles to form stitches in groups of a predetermined number each, and stop mechanism actuated by said operating means and adjustable 50 to stop said machine after the completion of a variable number of cycles.
2. In a machine for sewing on buttons, stitch forming mechanism, operating mechanism therefor including a controlling element having a 55 cycle of operation to cause said stitch forming mechanism to form a group of stitches of a predetermined number, and means adapted to be operated by said element at the completion of each cycle of operation thereof to stop the machine, said parts being adjustable to cause stopping of the machine after the completion of a 60 variable number of cycles of operation of said element to vary the number of groups of stitches formed.
- 65 3. In a machine for sewing on buttons, stitch forming mechanism, operating mechanism therefor, including a controlling element having a cycle of operation to cause said stitch forming mechanism to form a group of stitches comprising a predetermined number of attaching stitches and a tying stitch, and means adapted to be operated by said element at the completion of each cycle of operation thereof to stop the machine, said parts being adjustable to cause stopping 70 of the machine after the completion of a ping of the machine after the completion of a

variable number of cycles of operation of said element to vary the number of groups of stitches formed.

4. In a machine for sewing on buttons, stitch forming mechanism, operating mechanism therefor including a controlling element having a cycle of operation to cause said stitch forming mechanism to form a group of stitches of a predetermined number, and means adapted to be operated by said element at the completion of each cycle of operation thereof to stop the machine, said stopping means being adjustable for operation by said element at the completion of a variable number of cycles of operation thereof to vary the number of groups of stitches formed. 15

5. In a machine for sewing on buttons, a needle, cooperating looper elements, means for reciprocating said needle longitudinally, means for moving said needle laterally to cause it to pass through different holes in the button and for oscillating said looper elements, said last named means having a cycle of operation to cause the formation of a group of stitches of a predetermined number and means adapted to be operated by said last named means at the completion of each cycle of operation thereof to stop the machine, said parts being adjustable to cause stopping of the machine after the completion of a variable number of said cycles of operation to vary the number of groups of stitches formed. 20

25

6. In a machine for sewing on buttons, stitch forming elements, means for operating the same to form stitches, said operating means including a controlling element having a cycle of operation to cause the formation of a group of stitches of a predetermined number, means for shifting said stitch forming elements back and forth between two stitching positions after the formation of a group of stitches in each of said positions, and means adapted to be operated by said controlling 40 element at the completion of each cycle of operation thereof to stop the machine, said parts being adjustable to cause stopping of the machine after the completion of a variable number of cycles of operation of said element. 35

7. In a machine for sewing on buttons, the combination with stitch forming mechanism having cycles of operation to form groups of superimposed stitches of a predetermined number each, of means adapted to be operated at the completion of a cycle of operation of said stitch forming mechanism to stop the machine and adjustable to cause stopping of the machine after the completion of a variable number of cycles, whereby to vary the number of groups of stitches formed. 50

55 8. In a machine for sewing on buttons, stitch forming devices and actuating and controlling mechanism therefor adapted to cause the same to form automatically a plurality of groups of consecutive attaching stitches of a predetermined number each, said mechanism including means for causing said devices to form a tying stitch at the completion of each group of attaching stitches, and means for varying the number of groups of stitches automatically formed. 60

65 9. In a machine for sewing on buttons, stitch forming mechanism, means for operating the same in cycles to form stitches in groups of a predetermined number each, means for shifting the position of said mechanism between the formation of successive groups of stitches, and stop mechanism adjustable to stop the machine after the completion of a variable number of cycles. 70

75 10. In a machine for sewing on buttons, stitch forming mechanism, operating means for causing 75

- said stitch forming mechanism to form groups of stitches each including a predetermined number of attaching stitches followed by a tying stitch, and stop mechanism actuated by said operating means to stop the machine, said stop mechanism including means adjustable to cause actuation thereof after the completion of a variable number of tying stitches.
11. In a machine for sewing on buttons, stitch forming mechanism, means for operating the same in cycles to form groups of stitches of a predetermined number and character, and stop mechanism actuated by said operating means and operable to stop said machine only at the completion of a cycle, said stop mechanism being adjustable to cause the same to stop the machine after the completion of a variable number of cycles.
12. In a machine for sewing on buttons, stitch forming mechanism, means for operating the same in cycles to form superimposed stitches in groups of a predetermined number each, and stop mechanism adjustable to stop said machine after the completion of a variable number of cycles, said stop mechanism being adapted to be permanently set to control the number of cycles and the consequent number of stitch groups, whereby the machine may be repeatedly operated to form a recurrent series of such stitch groups without resetting said stop mechanism.
13. In a machine for sewing on buttons, stitch forming mechanism, means for operating the same in cycles to form groups of superimposed stitches of a predetermined number each, and stop mechanism adjustable to stop said machine after the completion of a variable number of cycles.
14. In a machine for sewing on buttons, stitch forming mechanism, means for operating the same in cycles to form groups of superimposed stitches of a predetermined number each, and stop mechanism actuated by said operating means and adjustable to stop said machine after the completion of a variable number of cycles.
15. In a machine for sewing on buttons, stitch forming mechanism, operating mechanism therefor including a controlling element having a cycle of operation to cause said stitch forming mechanism to form a group of superimposed stitches of a predetermined number, and means adapted to be operated by said element at the completion of each cycle of operation thereof to stop the machine, said parts being adjustable to cause stopping of the machine after the completion of a variable number of cycles of operation of said element to vary the number of groups of stitches formed.
16. In a machine for sewing on buttons, stitch forming mechanism, operating mechanism therefor including a controlling element having a cycle of operation to cause said stitch forming mechanism to form a group of stitches comprising a predetermined number of superimposed attaching stitches and a tying stitch, and means adapted to be operated by said element at the completion of each cycle of operation thereof to stop the machine, said parts being adjustable to cause stopping of the machine after the completion of a variable number of cycles of operation of said element to vary the number of groups of stitches formed.
17. In a machine for sewing on buttons, the combination with means for holding and posi-
- tioning a perforated button, of stitch forming mechanism, means for operating the same in cycles to form stitches through the holes of the button in groups of a predetermined number each, and stop mechanism adjustable to stop said machine after the completion of a variable number of cycles.
18. In a machine for sewing on buttons, the combination with means for holding and positioning a perforated button, of stitch forming mechanism, means for operating the same in cycles to form stitches through the holes of the button in groups of a predetermined number each, and stop mechanism actuated by said operating means and adjustable to stop said machine after the completion of a variable number of cycles.
19. In a machine for sewing on buttons, the combination with means for holding and positioning a perforated button, of stitch forming mechanism, operating mechanism therefor including a controlling element having a cycle of operation to cause said stitch forming mechanism to form a group of stitches of a predetermined number through the holes of the button, and means adapted to be operated by said element at the completion of each cycle of operation thereof to stop the machine, said stopping means being adjustable for operation by said element at the completion of a variable number of cycles of operation thereof to vary the number of groups of stitches formed.
20. In a machine for sewing on buttons, the combination with means for holding and positioning a perforated button, of stitch forming mechanism, operating means therefor including a controlling element having a cycle of operation to cause said stitch forming mechanism to form through the holes in the button a predetermined number of attaching stitches and thereafter to form a tying stitch, and means adapted to be operated by said element at the completion of each cycle of operation thereof to stop the machine, said parts being adjustable to cause stopping of the machine after the completion of a variable number of cycles of operation of said element.
21. In a machine for sewing on buttons, the combination with means for holding and positioning a perforated button, of stitch forming mechanism having cycles of operation to form through the holes of the button groups of stitches of a predetermined number each, and means adapted to be operated at the completion of a cycle of operation of said stitch forming mechanism to stop the machine and adjustable to cause stopping of the machine after the completion of a variable number of cycles.
22. In a machine for sewing on buttons, the combination with means for holding and positioning a button having a plurality of pairs of holes therethrough, of stitch forming mechanism, means for operating the same in cycles to form stitches in groups of a predetermined number each, each group of stitches being formed through a pair of holes in the button, means for shifting the position of said mechanism between the formation of successive groups of stitches to cause said stitches to be formed through different pairs of holes, and stop mechanism adjustable to stop the machine after the completion of a variable number of cycles.

FRANKLIN A. REECE.
